UNITED STATES PATENT OFFICE.

EDMUND R. WARE, OF WORCESTER, MASSACHUSETTS.

MEANS FOR MOUNTING AND SUPPORTING SOLID EMERY OR GRINDING WHEELS.

SPECIFICATION forming part of Letters Patent No. 244,699, dated July 19, 1881.

Application filed January 3, 1881. (No model.)

To all whom it may concern:

Be it known that I, EDMUND R. WARE, of Worcester, in the county of Worcester and State of Massachusetts, have invented certain new and useful Improvements in a Means for Mounting and Supporting Solid Emery or Grinding Wheels; and I declare the following to be a description of my said invention sufficiently full, clear, and exact to enable others skilled in the art to which it appertains to make and use the same, reference being had to the accompanying drawings, which form a part of this specification.

The object of my invention is to provide a means whereby emery-wheels may be mounted or supported in such manner as to avoid the injurious shock and jar tending to crack the wheel at the center or eye when in use, and to furnish means for supporting and holding the wheel in such a way that in case of fracture the pieces of the wheel are prevented from flying from the arbor, thus permitting of the wheels being run at a very high velocity with a degree of safety not attainable by the ordinary methods of mounting wheels; also, to afford facilities for adapting the supporting devices to the size of the grinding-wheel as it becomes worn away by use. I attain these objects by the means illustrated in the accompanying drawings, and herein described, the particular subject-matter claimed being hereinafter definitely specified.

In the drawings, Figure 1 is a vertical sectional view of an emery-wheel mounted in accordance with my invention. Fig. 2 is a side view, one half showing the grinding-wheel and the other half the face of one of the supporting-disks. Fig. 3 is a diagram showing the different sizes of supporting-disks. Fig. 4 shows one half-face view of the larger disk. Fig. 5 shows one half-face view of the smaller disk, and Fig. 6 is an enlarged sectional view of one of the bearing-studs.

The letter A denotes the arbor, on which is the back-collar A', the clamping-nut A², and binding-washer A³, arranged for confining the parts in the manner indicated.

B denotes the emery-wheel, which may be any ordinary solid grinding-wheel, although I prefer to have the wheel specially constructed

with a large central eye, B', and with slightly greater thickness near the center than at the periphery, as the enlargement of the eye saves stock in the formation of the wheels without reducing the available working parts, and the 55 inclination of the sides, by reason of greater thickness near the eye, gives a better hold for the supporting parts.

C indicates the supporting-disks, one of which is arranged at each side of the wheel B. 60 These disks are made with an outer shoulder, c, to fit the collar A' and washer A³, and with an inward-projecting ring or flange, C', to fit into the eye of the wheel B and retain it centrally true with the arbor, while the bearing- 65 faces of the disks are provided with numerous small studs or pins, D, of rubber, wood, paper, or other elastic or semi-elastic material, let into recesses or depressions C² formed in the metal of the disk, which studs or pins D take 70 the strain or bearing on the sides of the wheel B when the parts are set together, and firmly hold the wheel at numerous and distinct positions, and without permitting the metal of the disks to come into contact with the material 75 of the wheel, thus, while securely supporting the wheel, avoiding any liability of warping or straining it by undue pressure at any part, and at the same time giving an elastic support against the shock and jar of use. The studs 80 D retain their elasticity independent of each other, and each holds firmly to the portion of the wheel against which it rests, and in the larger-sized disks the studs are arranged so that any radial line across the face of the disk 85 will intersect one or more of the studs; hence there can be no fracture of the wheel from the center outward, except some of the studs have a hold on the pieces at both sides of the line of fracture, and thus retain the parts in place 90 after the wheel is broken.

The disks C, I provide in a series of three, each made with similar shoulder c and ring-flange C'. These disks are severally provided with studs D, as shown in Figs. 4, 2, and 5, 95 and are respectively interchanged as the wheel is worn away at the periphery.

If desired, the wheels B may be provided with the bearing studs or plugs, an example of which is illustrated at D', the depressions 100

for their reception being formed in the sides of the wheel when originally molded. This method is not, however, desirable, except, perhaps, for positions near the eye or in the smaller sizes of wheels.

The recesses in which the elastic studs or plugs D are set may be dovetailed or undercut, or somewhat larger than the studs, (see Fig. 6,) so as to allow for the expansion or swell of the studs by the pressure on their ends; and said studs may be secured in position in any suitable manner, as convenient.

What I claim as of my invention, and desire to secure by Letters Patent, is—

15 1. In combination with the grinding-wheel, a pair of clamping disks or plates provided with numerous independent projecting bearing-studs formed of elastic or semi-elastic material, which embrace the sides of the wheel

near the periphery thereof, substantially as and for the purpose set forth.

2. The combination, with the wheel-supporting plates C, having recesses or depressions C², of the independent elastic plugs or studs D, arranged substantially as and for the purposes set forth.

3. The combination, with the arbor A and grinding-wheel B, of the pair of interchangeable disks or plates C, provided with centering ring or flanges C', and elastic bearing-studs 30 D, for supporting the sides of said wheel, substantially as set forth.

Witness my hand this 7th day of December, A. D. 1880.

EDMUND R. WARE.
